[57] CLAIM

The ornamental design for a garment shield, as shown and described.

DESCRIPTION

FIG. 1 is a perspective view of a garment shield, showing my new design, the broken line showing of the garment is for illustrative purposes only and forms no part of the claimed design;

FIG. 2 is a top plan view thereof;

FIG. 3 is a bottom plan view thereof;

FIG. 4 is a left side elevational view thereof, the right side elevational view being a mirror image thereof;

FIG. 5 is a front elevational view thereof;

FIG. 6 is a rear elevational view thereof;

FIG. 7 is a top plan view of an alternate embodiment of the garment shield shown in FIG. 1;

FIG. 8 is a bottom plan view thereof;

FIG. 9 is a left side elevational view thereof, the right side elevational view being a mirror image thereof;

FIG. 10 is a front elevational view thereof; and,

FIG. 11 is a rear elevational view thereof.
